(57) **CLAIM**

The ornamental design for an industrial mixer, as shown and described.

DESCRIPTION

Industrial mixer

FIG. 1.1 is a perspective view of an industrial mixer showing the new design.

FIG. 1.2 is a partial bottom perspective view of the industrial mixer of FIG. 1.1 in a partially disassembled configuration. FIG. 1.3 is a partial top perspective view of the industrial mixer of FIG. 1.1 in a partially disassembled configuration. The dash-dash broken lines in the drawings represent portions of the industrial mixer that form no part of the claimed design.
